UNITED STATES PATENT OFFICE

ALFRED SCHAUMANN, OF BERLIN-FRIEDENAU, GERMANY

BODY ARMOR

Application filed March 16, 1929, Serial No. 347,712, and in Germany July 12, 1927.

This invention relates to armored clothing and its main object is the provision of a bulletproof garment which shall combine strength and resistability in use with a comparative flexibility and ease of wearing.

According to the invention this and other objects are achieved by arranging pieces, preferably plates of bulletproof material between several layers of a strong but flexible material, for example any suitable texture which, for greater strength may be interwoven with steel or wire netting, or to which hard material such as vulcanized fibre may be applied. The said plates of bulletproof material, according to the invention are applied in preferably checkered arrangement and so as to overlap each other in roof-like manner, each line or row of plates, however, being separated from the other by a layer of flexible material, and there are free spaces left between successive lines and/or rows, which are covered up by the underlying or overlying lines or rows of plates, and which are so disposed, that the ease of movement of the flexible material will not be impaired. The various layers of the flexible material with the armor plates attached thereto are superposed and fastened to each other so as to form one piece of comparatively great flexibility and utmost resistancy against bullet shots and other impacts.

The accompanying drawing illustrates by way of example a piece of armored texture for use in the making of the improved body armor.

Fig. 1 is an elevational view, while

Fig. 2 is a section taken on line A—B of Fig. 1.

In these figures the letter *d* is used to denote three layers of any suitable texture which are provided with distanced pieces or plates of bulletproof material *a*, *b*, and *c*. The arrangement of these plates on the various layers *d* is such that, when the three layers *d* with their armor plates are superposed and fastened to each other, a body armor is obtained which, although maintaining a high degree of flexibility will yet ensure full safety against the penetration of bullets because the armor plates *a*, *b*, and *c*

cover the entire surface of the garment. If desired, the individual layers *d* may be strengthened by interwoven steel wire or netting, or by the application of hard materials, without thereby impairing their flexibility to any material extent. These strengthening means are not shown in the drawing as their arrangement is immaterial to the understanding of the invention.

It is evident that the invention may be subjected to different changes or alterations to suit special wishes or requirements. Also the form and size of the armor plates upon the various layers of texture, as well as their number and disposition may be as desired, it being merely of importance that, when the various layers are superposed and fastened to one another, a mutual overlapping of the plates and filling up of the free spaces of adjacent lines or rows of plates is ensured.

What I claim is:—

1. A body armor, comprising a number of flexible layers, plates of bulletproof material arranged in spaced relation upon each of said layers, said flexible layers being superposed so that the free spaces of each layer are covered by plates on the other layers.

2. A body armor comprising a number of flexible layers, plates of bulletproof material arranged in spaced checkered relation upon each of said layers, said flexible layers being superposed so that the free spaces of each layer are covered by plates on the other layers and so that the various juxtaposed plates overlap each other.

In testimony whereof I affix my signature.

ALFRED SCHAUMANN.
